UNITED STATES PATENT OFFICE.

GUSTAF ARVID ANDERSON, OF WAYNESBORO, PENNSYLVANIA, ASSIGNOR TO THE GEISER MANUFACTURING COMPANY, OF WAYNESBORO, PENNSYLVANIA.

TANK FOR TRACTION-ENGINES.

No. 818,217.

Specification of Letters Patent.

Patented April 17, 1906.

Application filed November 18, 1905. Serial No. 288,083.

To all whom it may concern:

Be it known that I, GUSTAF ARVID ANDERSON, a citizen of the United States, residing at Waynesboro, in the county of Franklin and State of Pennsylvania, have invented 5 certain new and useful Improvements in Tanks for Traction-Engines; and I do hereby declare the following to be a full, clear, and exact description of the invention, such as will 10 enable others skilled in the art to which it app- pertains to make and use the same.

This invention relates to water-supply tanks for traction-engines; and it consists in 15 the novel construction and combination of the parts whereby the water-tanks are supported at the rear part of the traction-engine close behind and partially over the traction- 20 wheels.

In the drawings, Figure 1 is a side view of 25 the rear part of a traction-engine provided with water-tanks according to this invention. Fig. 2 is a plan view of the same.

A is the fire-box end portion of the boiler of a traction-engine of any approved construction.

B represents two frames secured to the sides of the boiler at its rear end.

C represents the traction-wheels mounted on a shaft or axle c, which is journaled in 30 bearings b, secured to the said frames.

D is a tubular beam which is supported behind the traction-wheels at a convenient height above the ground. This beam is supported by means of bars E and braces F. These bars and braces are secured to the frames B at one end and at the other end are provided with suitable fastening devices, which secure them to the tubular beam. The braces are inclined, and their upper ends are secured to the middle parts of the frames above the said bars.

F' represents braces between the middle part of the tubular beam and the said frames, and f is a draft attachment for the traction-engine connected to the tubular beams in front of the braces F'.

G represents two similar water-tanks the upper portions of which are rectangular. The lower front side g of each tank is curved 50 to conform with the outline of the traction-wheel in front of it. The bottom h of the tank is narrow and rounded, and the lower portion of the rear side of the tank is in-

clined, so that it is substantially at a tangent to the periphery of the traction-wheel.

55

H represents brackets arranged between the tubular beam and the bottom of the water-tank. These brackets have rounded seats which fit against the beam and the tank-bottom.

60

I represents braces between the tanks and the frames B. The front ends of these braces are secured to the frames at any convenient points, and their rear ends engage with brackets i, which are secured to the two adjacent sides of the two tanks.

65

The two tanks project partly over the rear portions of the two traction-wheels, and they afford room for a large supply of water. When the tanks are constructed and supported in this manner, they do not occupy 70 too much space and do not overbalance the front end of the engine.

75

The water-tanks are preferably made of thin sheet-iron riveted to angle-irons in the usual manner of making tanks. These tanks permit the traction-engine to be provided with a short driving-platform, and the tanks can be made of any desired capacity by extending their rear portions. For the purpose 80 of arranging the tanks to the best advantage the center of gravity of the said tanks is arranged a little to the rear of the vertical center line of the beam D when the traction-engine is on level ground.

85

What I claim is—

1. The combination, with a boiler and traction-wheels, of a beam supported from the said boiler and arranged crosswise at the rear of the said wheels, and two tanks supported by the end portions of the said beam and provided with upwardly and forwardly extended front portions which project part way over the said wheels.

90

2. The combination, with the boiler and traction-wheels of a traction-engine, of a beam supported from the said boiler and arranged crosswise at the rear of the said wheels, and two tanks supported by the said beam, each said tank having a rectangular upper part, a narrow rounded bottom, an inclined portion at the lower part of its rear side, and a curved portion at the lower part of its front side which extends part way over the traction-wheel in front of it.

95

3. The combination, with the boiler and

100

105

traction-wheels of a traction-engine, of a beam supported from the said boiler and arranged crosswise at the rear of the said wheels, two tanks supported by the said beam and provided with upwardly and forwardly extended front portions which project part way over the said wheels, brackets secured to the adjacent sides of the said tanks, and braces secured to the said brackets at one end and connected with the boiler at the other end.

4. The combination, with a boiler and traction-wheels, of a beam supported from

the said boiler and arranged crosswise at the rear of the said wheels, and two tanks supported by the end portions of the said beam and arranged with their centers of gravity normally to the rear of the center of gravity of the said beam. 15

In testimony whereof I have affixed my 20 signature in the presence of two witnesses.

GUSTAF ARVID ANDERSON.
